UNITED STATES PATENT OFFICE.

GOTTDANK L. KOTHNY AND ROBERT SUCZEK, OF PHILADELPHIA, PENNSYLVANIA,
ASSIGNORS TO C. H. WHEELER MANUFACTURING COMPANY, OF PHILADELPHIA,
PENNSYLVANIA, A CORPORATION OF PENNSYLVANIA.

AUTOMATIC EJECTOR CONTROL.

1,240,858.

Specification of Letters Patent. Patented Sept. 25, 1917.

Application filed March 23, 1916. Serial No. 86,075.

To all whom it may concern:

Be it known that we, GOTTDANK L. KOTHNY and ROBERT SUCZEK, subjects of the Emperor of Austria-Hungary, residing at Philadelphia, county of Philadelphia, State of Pennsylvania, have invented new and useful Improvements in Automatic Ejector Controls, of which the following is a specification.

10 Our invention relates to vacuum producing apparatus which is automatically controlled with respect to the supply of motive fluid or its pressure, utilized, as in ejector apparatus, for producing or maintaining a 15 vacuum.

It is the object of our invention to provide a system wherein an ejector is employed for producing or maintaining a vacuum, as in a steam condenser or other device, and 20 wherein exhaust or live steam, or motive fluids of different kinds or pressures, may be employed in the ejector together with an automatic control which shall insure the ejector receiving sufficient of either of the 25 motive fluids independently of variations in the supply or pressure of at least one of them.

For an illustration of some of the forms 30 our invention may take, reference is to be had in the accompanying drawing, in which:

Figure 1 is an illustration of a system embodying one form of our invention.

Fig. 2 is a sectional view, some parts in elevation, of the automatically controlled 35 valves.

Fig. 3 is an illustration of an embodiment of our invention when applied to a jet condenser.

In Fig. 1, C represents a steam condenser, 40 such as a surface condenser, having the exhaust steam inlet a and the tubes b, only a portion of which is shown, which conduct the cooling water which is delivered thereto through the pipe c from the centrifugal or 45 other pump P. The condensed steam or condensate collects in the bottom of the condenser C and is conducted through pipe d to the condensate pump P¹ and delivered

thereby to any suitable point through the pipe e. The pumps P and P¹ are shown as 50 having a common shaft driven by a steam engine or motor, such as a steam turbine T. Steam for driving the turbine T is delivered through the pipe f controlled by the valve g.

The exhaust steam from the turbine T is 55 delivered into the pipe h which is provided with the relief valve i which, when the pressure of exhaust steam in the pipe h exceeds a predetermined value, opens and allows escape thereof to atmosphere, to the boiler 60 feed water heater, or to any other place or device. Ordinarily, however, the exhaust steam will pass through the pipe h and through the swinging check valve j into the pipe k, controlled by ordinary hand valve m, 65 to the ejector E having the chamber n into which projects the expansion nozzle o receiving the steam from pipe k. The chamber n also communicates by passage p beneath the baffle q with the steam space of the 70 condenser C to extract therefrom the air or other gases or fluid to maintain the desired vacuum therein. The steam issuing through the nozzle n entrains the air or gas and the mixture is delivered through the ejector 75 diffuser r through the pipe s.

It is desirable to always maintain a high vacuum in the condenser C and it is therefore important that the ejector E is supplied at all times with sufficient steam or 80 motive fluid.

It frequently occurs, however, that the amount of exhaust steam available from the turbine T, as when the load upon the turbine T decreases, is insufficient to maintain 85 the proper vacuum, through the agency of the ejector E, within the condenser C. In such case other or additional steam is automatically supplied to the ejector E so that it may maintain the proper vacuum in the 90 condenser C.

This is effected by delivering some of the steam from the pipe f to the ejector E.

This is automatically accomplished by an arrangement of the character illustrated in 95 Fig. 2 where f represents the steam supply

pipe which communicates with a chest or chamber t having the steam outlets v and w , of which the former conducts steam to the turbine T for driving the same and w 5 delivers into the pipe x , Fig. 1, having a swing check valve y and connecting with the pipe k to the right of the check valve j .

Communication between the chest t and the outlets v and w is controlled by the 10 valves a^1 and a^2 , Fig. 2, these valves being shown open and closed, respectively, and secured upon the valve rods b^1 and c^1 connected to the lever d^1 pivotel at e^1 and controlled by the fly ball or other governor G 15 driven or rotated by the turbine T .

The operation is as follows:

Assuming the turbine T to be loaded, it 20 delivers sufficient exhaust steam through the pipe h , valve j and pipe k to the ejector E to maintain the desired vacuum in the condenser C .

Should the load upon the turbine T change, that is, should it for example decrease, the governor will move the lever d^1 25 in a counterclockwise direction about its pivot e^1 , thereby decreasing the opening of the valve a^1 to reduce the amount of steam to the turbine T and opening the valve a^2 , thereby allowing steam from the pipe f to 30 pass through chamber t and through outlet w , pipe x and check valve y through pipe k to the ejector E which now receives sufficient steam for maintaining the vacuum in the condenser C .

35 By this automatic action, when the supply of exhaust steam through the pipe h falls to or below a predetermined minimum steam from the pipe f will be delivered to the ejector E either to make up for the decreased 40 amount of steam delivered thereto from the pipe h , or entirely replacing the steam from pipe h by steam from the pipe f .

And in case the amount of exhaust steam delivered from the turbine T to the pipe h 45 is greater than that which is necessary for the ejector E , the relief valve i will open and allow escape of any excess steam.

In Fig. 3 our automatic arrangement is shown in connection with a jet condenser J 50 having the usual water inlet f^1 delivering through the nozzles g^1 , and having the inlet h^1 for the steam to be condensed. The ejector E is connected as shown, and the turbine T drives the submerged centrifugal pump P^1 55 for removing the condensate and condensing water. Here again by a system of piping and valves and controls similar to those of Fig. 1, upon decrease of exhaust steam through the pipe h to or below a predetermined minimum, steam is delivered to 60 the ejector E from pipe x .

What we claim is:

1. The combination with a chamber, of an 125 ejector for producing a vacuum therein, a

plurality of sources of motive fluid for said 65 ejector, and automatic means for opening communication between one of said sources and said ejector upon decrease of motive fluid supplied by another of said sources.

2. The combination with a chamber, of an 70 ejector for producing a vacuum therein, a source of exhaust steam for said ejector, a source of live steam, and automatic means for opening communication between said source of live steam and said ejector upon 75 change in supply of exhaust steam.

3. The combination with a condenser, of an 80 condensate pump therefor, a steam motor for driving said pump, an ejector for withdrawing air or gas from said condenser, an exhaust steam connection from said motor to said ejector, and means responsive to change of load on said motor for connecting said ejector to another source of steam.

4. The combination with a chamber, of an 85 ejector for producing a vacuum therein, a steam motor, a pipe delivering steam exhausted from said motor to said ejector, a check valve in said pipe, a pipe extending from another source of steam connecting with said first named pipe at a point between said check valve and said ejector, and means responsive to change of load on said 90 motor controlling supply of steam from said second named source into said second named 95 pipe.

5. The combination with a chamber, of an 100 ejector for producing a vacuum therein, a source of steam, a pipe connecting said source with said ejector, a check valve in said pipe, a pipe extending from another source of steam connecting with said first named pipe at a point between said check 105 valve and said ejector, and automatic means for controlling flow of steam from said second named source into said second named pipe.

6. The combination with a chamber, of an 110 ejector for producing a vacuum therein, a motor, a pipe delivering steam exhausted from said motor to said ejector, a check valve in said pipe, a pipe extending from another source of steam connecting with said first named pipe at a point between said check 115 valve and said ejector, means responsive to change in load on said motor controlling flow of steam from said second named source into said second named pipe, and a relief valve for said exhaust steam.

7. The combination with a chamber, of an 120 ejector for producing a vacuum therein, a source of exhaust steam, a pipe connecting said source with said ejector, a check valve in said pipe, a pipe extending from another source of steam connecting with said first 125 named pipe at a point between said check valve and said ejector, automatic means for admitting steam from said second named

source into said second named pipe, and a relief valve for said exhaust steam.

8. The combination with a chamber, of an ejector for producing a vacuum therein, a steam motor, a pipe delivering steam exhausted from said motor to said ejector, a check valve in said pipe, a pipe extending from another source of steam connecting with said first named pipe at a point between 5 said check valve and said ejector, means responsive to change in load on said motor for controlling flow of steam from said second named source into said second named pipe, and a check valve in said second named 10 pipe.

9. The combination with a chamber, of an ejector for producing a vacuum therein, a source of exhaust steam, a pipe connecting said source with said ejector, a check valve 20 in said pipe, a pipe extending from another source of steam connecting with said first named pipe at a point between said check valve and said ejector, automatic means for admitting steam from said second named 25 source into said second pipe, and a check valve in said second named pipe.

10. The combination with a chamber, of an ejector for producing a vacuum therein, a steam motor, a pipe delivering steam exhausted from said motor to said ejector, a check valve in said pipe, a pipe extending from another source of steam connecting with said first named pipe at a point between 30 said check valve and said ejector, means responsive to change in load upon said motor for controlling flow of steam from said second named source into said second named pipe, a relief valve for said exhaust steam, and a check valve in said second named 35 pipe.

11. The combination with a chamber, of an ejector for producing a vacuum therein, a source of exhaust steam, a pipe connecting said source with said ejector, a check valve 40 in said pipe, a pipe extending from another source of steam connecting with said first named pipe at a point between said check valve and said ejector, automatic means for admitting steam from said second named 45 source into said second named pipe, a relief valve for said exhaust steam, and a check valve in said second named pipe.

12. The combination with a chamber, of an ejector for producing a vacuum therein, a steam motor, a governor therefor, an exhaust steam connection from said motor to said ejector, and a connection from said 50 ejector to a second source of steam controlled by said governor.

13. The combination with a chamber, of an ejector for producing a vacuum therein, a steam motor, a governor therefor, valves 60 opened and closed respectively by said governor, one of said valves controlling admission of steam to said motor, and another of 65 said valves controlling admission of steam to said ejector.

14. The combination with a chamber, of an ejector for producing a vacuum therein, a steam motor, a governor therefor, valves 70 opened and closed respectively by said governor, one of said valves controlling admission of steam to said motor, another of said valves controlling admission of steam to said ejector, and an exhaust steam connection from said motor to said ejector.

15. The combination with a condenser, of a cooling water pump therefor, a steam motor for driving said pump, an ejector for withdrawing air or gas from said condenser, an exhaust steam connection from said motor to said ejector, and means responsive to change of load on said motor for connecting said ejector to another source of steam.

16. The combination with a chamber, of an ejector for producing a vacuum therein, a source of motive fluid for said ejector, a motor, and means responsive to change of load on said motor controlling connection between said ejector and said source of motive 90 fluid.

17. The combination with a chamber, of an ejector for producing a vacuum therein, a source of motive fluid, a motor, and a governor controlling said motor and a connection 95 between said source of motive fluid and said ejector.

18. The combination with a condenser, of means for removing condensate therefrom, an ejector for removing air or gas from said condenser, a source of motive fluid, and means responsive to variations in amount of condensate controlling a connection between said source of motive fluid and said 100 ejector.

19. The combination with a condenser, of means delivering cooling water thereto, an ejector for removing air or gas from said condenser, a source of motive fluid, and means responsive to changes in amount of 110 cooling water delivered to said condenser controlling connection between said source of motive fluid and said ejector.

20. The combination with a condenser, of a cooling water pump therefor, a steam motor for driving said pump, an ejector for withdrawing air or gas from said condenser, an exhaust steam connection from said motor to said ejector, and means responsive to change in load on said motor for connecting said ejector to a second source of steam.

21. The combination with a condenser, of a condensate pump and a cooling water pump therefor, a steam motor for driving said pumps, an ejector for withdrawing air or gas from said condenser, an exhaust steam connection from said motor to said ejector, and means responsive to change of load on 125

said motor for connecting said ejector to a second source of steam.

22. The combination with a condenser, of pumping means coöperating therewith, an 5 ejector for removing air or gas therefrom, means delivering to said ejector steam whose quantity varies with the load upon said pumping means, and automatic means causing increase of steam delivery to said ejec-

tor upon decrease of the steam whose amount 10 varies with the load upon said pumping means.

In testimony whereof we have hereunto affixed our signatures this 21st day of March, 1916.

GOTTDANK L. KOTHNY.
ROBERT SUCZEK.
